Primary Examiner — Prabhakar Deshmukh(74) *Attorney, Agent, or Firm* — Li & Cai Intellectual Property (USA) Office(57) **CLAIM**

The ornamental design for a “part of roof-mounted media player with sliding rails,” as shown and described.

DESCRIPTION

FIG. 1 is a perspective view of a part of roof-mounted media player with sliding rails showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view in a usage condition thereof; and,

FIG. 9 is a perspective view with the screen folded thereof. The broken line showing of the environment is for illustrative purposes only and forms no part of the claimed design.
